UNITED STATES PATENT OFFICE.

JAMES F. BURNS, OF PHILADELPHIA, PENNSYLVANIA.

ELECTRIC SWITCH.

1,191,924.

Specification of Letters Patent.

Patented July 18, 1916.

Application filed November 10, 1915. Serial No. 60,740.

To all whom it may concern:

Be it known that I, JAMES F. BURNS, a citizen of the United States, residing in Philadelphia, Pennsylvania, have invented 5 certain Improvements in Electric Switches, of which the following is a specification.

My invention relates to electrical switches, and more particularly to inclosed switches, in which the switch mechanism is inclosed 10 within a box or casing, with provision for operating the switch from the outside without opening the box.

The common knife-switch as ordinarily used in exposed switches, is constructed and 15 mounted in such a manner that a downward or outward pull upon the operating handle will open the switch and an upward or inward push will close it.

One object of my invention is to provide 20 an inclosed switch operable by the same general character of motions to which the operator is accustomed with exposed switches.

Another object is to provide the inclosed 25 switch with external operating means of such character as will enable the operator readily to determine the limits of the full opening and closing motions.

In the accompanying drawings:—Figure 30 1 is a sectional view of an inclosed switch embodying my invention, the switch being closed; Fig. 2 is a similar view with the switch shown in open position; Fig. 3 is a perspective view; and Fig. 4 is a plan view 35 with the cover thrown back and partly broken away, and with the switch closed.

In the drawings 1 indicates the box or casing, usually of metal, and having hinged cover 2.

40 The switch proper comprises insulating base 3, secured to the wall of the box, the usual switch contact 4, knife switch blades 5, with cross-piece 6, fuses 15, and binding posts, all disposed in the usual manner.

45 Centrally secured to the cross-piece 6 is the operating rod 7, which extends through the end wall of the inclosing casing and terminates in the handle 8. In order that the pull upon the cross-piece 6 in opening

50 the switch may be in the general direction of the arc through which said cross-piece must travel, the rod 7 must have an angular relation with respect to the longitudinal direction of the switch-blade, when in closed 55 position, as shown in Fig. 1, and to insure

this, I provide a bearing or guide for the rod 7 in the end wall of the inclosing casing, at a point above the switch-blades. In the particular embodiment of the invention illustrated in the drawings, this bearing or 60 guide is provided by an ear or lug 9 projecting from the end wall of the casing, said lug having an aperture 10 through which the operating rod 7 passes. The end flange and end wall of the cover 2 are slotted at 65 11 and 12 respectively to permit the closing of the cover without interference by the upward or angular projection of the operating rod.

In the present instance as the box 1 is 70 shallow, I have provided the cover 2 with an extension 14, forming a chamber of sufficient depth to accommodate the switch-blades when in full open position and in the present instance this chamber also receives the lug 9 projecting from the end wall of the box. It will be understood, however, that in carrying out my invention, I do not confine myself to any particular form or shape of box or inclosing casing. It will 75 also be apparent that with an inclosing casing of somewhat greater depth than the particular form illustrated, an independent ear or lug such as 9 may be dispensed with as the end wall itself may be apertured to furnish a guide or bearing for the operating rod 7.

To permit the operator to determine readily the full open position of the switch, I may provide the rod 7 with any suitable 90 stop as, for example, the bend 13 adapted to abut against the end wall of the inclosure, as shown in Fig. 2.

As ordinarily used, the box or casing will be secured to a wall or other suitable surface in vertical position, with the wall through which the operating rod projects serving as the bottom wall of the casing. There will thus be no slots or other openings in the casing through which dust may enter, 95 except for the small opening at the bottom wall which being located underneath the box is in the least exposed position. This is an important practical advantage.

I claim:

1. In an electric switch, a box, a switch mechanism within said box, a hinged cover forming, with said box, a complete inclosing casing for said switch mechanism, an operating rod for said switch mechanism pro- 100 105 110

jecting through said cover, said cover being slotted to permit the raising and lowering of the same.

2. In an electric switch, a box, switch mechanism within said box, a rod secured at one end to said switch mechanism and at the opposite end projecting beyond a wall of said box, a guide for said rod, said guide projecting upwardly from said wall, a hinged cover for said box having a chamber into which said guide projects, a wall of said cover being slotted to permit the opening and closing of the same.

3. An electric switch with an inclosing casing, a switch mechanism within said casing, including a hinged contact member adapted, upon the opening of said switch, to swing toward a wall of said casing, an operating rod secured to said hinged contact

member and extending through said wall, 20 means on said wall for maintaining said rod in operative position, and a hinged cover on the casing having a slot in that portion which passes over the operating rod.

4. An electric switch with an inclosing 25 casing, a switch mechanism within said casing, an operating rod for said switch mechanism, said rod extending through a wall of said casing, a lug on said wall for supporting said operating rod, a stop on said operating rod arranged to coöperate with said lug for limiting the motion of the rod, and a hinged cover on the casing having a slot 30 through which the operating rod extends, said slot permitting the opening and closing 35 of the cover.

JAMES F. BURNS.
